His Attorney.

UNITED STATES PATENT OFFICE.

WILLIAM J. A. LONDON, OF SPRINGFIELD, MASSACHUSETTS, ASSIGNOR TO GENERAL ELECTRIC COMPANY, A CORPORATION OF NEW YORK.

ELASTIC-FLUID TURBINE.

1,297,878.

Specification of Letters Patent. Patented Mar. 18, 1919.

Application filed February 6, 1918. Serial No. 215,573.

To all whom it may concern:

Be it known that I, WILLIAM J. A. LONDON, a subject of the King of Great Britain, residing at Springfield, in the county of 5 Hampden, State of Massachusetts, have invented certain new and useful Improvements in Elastic-Fluid Turbines, of which the following is a specification.

The present invention relates to elastic 10 fluid turbines and especially turbine driven sets in which the turbine casing is connected to the casing of the driven machine by girder members, the whole forming a set having a rigid frame construction.

15 The object of my invention is to provide an improved structure in a set of this character, and for a consideration of what I believe to be novel and my invention attention is directed to the accompanying specification and the claims appended thereto.

20 In the drawing, Figure 1 is a top plan view of a turbine set or installation embodying my invention; Fig. 2 is an end view taken on line 2—2, Fig. 3, and Fig. 3 is a 25 side elevation partly in section and with parts broken away.

Referring to the drawing, 5 indicates 30 an elastic fluid turbine and 6 a driven member, for example a generator. The shaft 7 of the turbine is supported in bearings 8 and 9 and carries bucket wheels, as indicated at 10. The low pressure end of the turbine is shown as having a conical shaped casing 11 which is split horizontally 35 and which may terminate at the last stage wheel. The turbine casing and the casing of the driven member 6 are rigidly connected to each other by girder members 12, two such members being illustrated. These are 40 preferably formed integral with the head 13 of the driven machine and are connected to the turbine casing 11 by a ring of bolts 14. Surrounding the casing 11 is an exhaust housing, the opening of which connects with a condenser 15 which may be of any suitable structure. The exhaust housing 45 comprises a portion 16 which surrounds the low pressure end of the turbine casing and is fastened to a flange 17 thereon by 50 bolts 18 or other suitable means, and a portion 19 which forms an end wall of the exhaust housing. The surrounding portion 16 of the exhaust housing is preferably formed in two halves, being split horizontally at 55 the axis of the turbine shaft, and it is

braced by rods or bars 20 to give it strength and rigidity. The portion 19 of the exhaust housing is formed as an integral part of the girder members 12 and is fastened to the portion 16 by bolts 21. At its central 60 portion it surrounds the shaft 7 and has fastened to it a flange 22 on the packing casing 23. 24 is a supporting foot for the turbine and 25 is a box girder structure for strengthening it. Surrounding the body of 65 the turbine is a casing 26 between which and the turbine casing is packed suitable heat insulating material 27.

It will thus be seen that the exhaust housing is formed as a separate element which is 70 attached to the turbine casing proper and comprises essentially two portions, one which surrounds the exhaust end of the turbine casing and is formed in two parts, and another which forms an end wall and is 75 also formed in two parts, one integral with each girder member 12. In other words, the exhaust housing and girder members, together comprise four castings. This arrangement has the advantage that the patterns for casting these four parts are of a 80 relatively simple character and the shape of the castings is such that all the surfaces requiring finishing are readily accessible and the finishing work can be performed on a 85 boring mill. Furthermore, although the assembled exhaust housing may be large, the machine work can be performed on a relatively small boring mill.

Since the exhaust housing is a structure 90 separate from the turbine proper and attached thereto, it will be seen that by very simple changes in the location of the supporting foot on the exhaust housing, the exhaust opening may be made to face in any 95 desired direction. The structure is thus adapted to permit of slight changes in the exhaust housing structure at a minimum expense. Also the same exhaust housing patterns may be adapted for turbines of different size.

In accordance with the provisions of the patent statutes, I have described the principle of operation of my invention, together with the apparatus which I now consider to 105 represent the best embodiment thereof; but I desire to have it understood that the apparatus shown is only illustrative and that the invention can be carried out by other means.

What I claim as new and desire to secure by Letters Patent of the United States, is:

1. In a turbine driven set, the combination of a turbine casing, a driven machine having a casing, girder members connecting said casings together, and an exhaust housing comprising a main part which surrounds the low pressure end of said turbine casing and is fastened thereto, and an end portion, 10 said end portion being formed of wall members carried by said girder members and fastened to the main portion of the exhaust housing.
2. In a turbine driven set, the combination of a turbine casing, an exhaust housing surrounding the low pressure end of said casing and bolted directly thereto, a driven machine having a casing, and girder members connecting said casings together, an 15 end portion of said exhaust housing being formed by walls which are integral with said girder members and are fastened to the remainder of the exhaust housing, whereby such end portion of the exhaust housing

may be cast as a part of the girder members. 25

3. In an elastic fluid turbine, the combination of a turbine casing, an exhaust housing wall surrounding the same and split axially into two parts, said wall being fastened at one end to the turbine casing at a point spaced from the low pressure end thereof and open at the other end, and a wall which surrounds the turbine shaft and forms a closure for said open end. 30 35

4. In a turbine driven set, the combination of a turbine having a casing, a driven machine having a casing, girder members connecting said casings, a wall which is split axially and surrounds the low pressure end 40 of the turbine casing to form an exhaust chamber, said wall being fastened to the turbine casing at one end and being open at the other end, and walls carried by said girder members which close said open end. 45

In witness whereof, I have hereunto set my hand this 1st day of February, 1918.

WILLIAM J. A. LONDON.
